REGISTER-RECEPTACLE FOR STAMPS,
TAGS, AND THE LIKE

Harry L. Shulman, Atlanta, Ga.

Application January 15, 1943; Serial No. 472,526

1 Claim: (Cl. 232—4)

This invention relates to receptacles broadly, and particularly to what is herein termed a register-receptacle, an object of the invention being to provide means whereby articles such as ration stamps, tags, and like identifying devices may be quickly and easily deposited in and automatically allotted to individual trays or containers therefor in stores or other places where such means may be used to advantage, thereby simplifying the task of collecting, arranging and sorting the stamps or other articles and also facilitating the work of a checker, cashier or other employee to a marked degree.

The collection of ration stamps, tags and the like largely used in commercial transactions in stores and other places of business imposes an added burden on the employees, resulting in confusion and slowing down of trade, particularly in self-service stores where a checker oftentimes has to take care of a long line of customers during rush hours. In many instances, the clerk or checker becomes utterly confused and much time is lost in subsequently sorting the stamps or tags, and in some instances the stamps are trampled underfoot and mutilated beyond recognition. The present invention has effectively solved this problem.

Other objects include the provision of a multi-compartment register-receptacle which may be supported in an upright position adjacent a cash register or hung on the wall in any convenient location; to provide a device of this character which may be easily manufactured from cardboard or other readily available material at an unusually low cost; and to generally improve and simplify such receptacles.

The foregoing and other objects and advantages will become apparent in view of the following description taken in conjunction with the drawing, wherein:

Figure 1 is a view in front elevation of a register-receptacle in accordance with the invention;

Fig. 2, a side or edge elevation, and

Fig. 3, a view in perspective of the receptacle showing the lid raised and one of the individual trays removed and in projected position.

Referring to the drawing in detail, the register-receptacle comprises a main tray compartment 10, preferably of rectangular formation, having therein a plurality of individual trays or receptacles 11, each of the latter being removable as indicated in Fig. 2. These trays or individual receptacles are also preferably of rectangular

formation and together as a group fit snugly in the main compartment 10.

A lid or cover 12 is adapted to fit over the main receptacle 10 and is formed with a series of register slots 13, one for each of the individual containers or trays 11. These slots 13 are preferably formed on the lid at points which will bring the slots adjacent the top of each individual tray. The slots are designated by suitable indicia, depending upon the type of stamps or tags for which the register is adapted. In the present instance, alphabetical letters are used. However, these may be made standard and a chart prepared to assist in allocating and sorting the stamps. Also, the respective trays may be designated according to name, brand, or like easily-read designation which will facilitate the work of a checker or clerk during rush hours. In the present instance, the main tray compartment 10 is adapted to contain twenty trays, but it will be obvious that this number may be increased or decreased in accordance with the type of service to be performed.

In order that the register-receptacle may be supported on a counter in an upright position adjacent a cash register or hung on a wall or other convenient support, an easel is provided and generally indicated at 14, said easel preferably being made up of a piece of cardboard or the like having a flat central portion 16 suitably secured to the back of the main tray compartment 10, and a pair of divergent side panels defining legs 17 and 17'. As can be readily observed from Fig. 1, the top of the central portion 16 terminates in a handle portion 18 having a slot 19 therein whereby the register-receptacle may be easily carried from place to place or hung from a nail or the like.

Each of the side panels which provide the legs 17, 17' is foldable and is formed with a cut-out portion 20 including a slot 20', and the central portion 16 is provided with a latching tab 21 which may be formed by cutting out a suitable area of said portion and scoring along the bottom 45 of the tab to provide a hinge, so that the tab may be bent down into latching position when it is desired to set up the easel. The particular shape of the cut-out portions 20 and 20' results in the formation of an inward latch projection 22 and a stop 23.

The latch projection 22 serves as a retainer against back or return movement of the tab 21 when it is in its down or latching position, while the stop 23 limits the down position of said tab.

In use, the register-receptacle may be placed

on a counter adjacent a cash register or it may be hung on a wall or like support. When the clerk or checker receives a ration stamp, tag or the like and which is generally delivered with the money for the purchase, the stamps or tags are placed in the register in the slots adapted to receive the same. If it is desired to fold the legs 17, 17', it is only necessary to push the tab 21 upwardly past the latch projection 22 and flat against the back portion 16 of the easel, whereupon the said legs may be folded towards one another (or outwardly if desired). To bring the legs of the easel to operative position, it is only necessary to turn them outwardly and bring the tab or latch 21 down into registration with the slot 20. Whether or not the legs are folded when the register-receptacle is hung from a wall depends upon certain conditions. Thus, if hung below the normal level of use, the legs may be set up to cause the face of the register to tilt forwardly and upwardly whereas if hung above such level, the legs may be folded to bring the face of the register in a substantially vertical plane.

The entire register-receptacle may be made of cardboard, wood, metal or any other available material. The simplicity of manufacture will be obvious. The easel may be made separately in one stamping operation and cemented or otherwise attached to the back of the main tray compartment 10. Actual use has demonstrated the

time and labor saved by the relatively simple device.

It will be understood that certain changes in construction and design of my improved register-receptacle may be made without departing from the spirit and scope of the invention as defined by the appended claim.

What is claimed is:

10 A register-receptacle for stamps, tags, and like identifying media, comprising a main base container, a plurality of individual trays removably disposed in said container, a cover engaging over said container and formed with a plurality of slots, one for each tray, said cover bearing identifying indicia for said slots, and a foldable easel connected to the back or outer side of said main receptacle forming strengthening and reinforcing means for the box, said easel being provided with side panels foldable inwardly and outwardly to provide legs for the easel and the portion of the easel which is secured to the main container being provided with a hinged tab adapted to engage said legs and support the latter in set-up position, the upper portion of said easel projecting 20 above the main container and being formed with a finger grip and hanging slot to provide a handle for the receptacle and also to provide means whereby the receptacle may be hung from a wall or other convenient support.
